CLAIM

The ornamental design for a motorcycle tire, as shown
and described.

DESCRIPTION

FIG. 1 is a perspective view of a motorcycle tire showing
my new design, it being understood that the tread
design is repeated uniformly throughout the circumfer-
ence of the tire and the opposite side is the same as that
shown.

FIG. 2 is a front elevational view thereof;

FIG. 3 is a side elevational view thereof;

FIG. 4 is a rear elevational view thereof; and

FIG. 5 is an enlarged fragmentary front elevation view
thereof.

FIG. 1

FIG. 2

FIG. 3

FIG. 4

FIG. 5
